CURTAIN HEADING TAPE

George Frederick French and Roger French, Hale,
and Brindley Jack Brown, Littleborough, Eng-
land; said Brown assignor to said George Fred-
erick French and said Roger French

Application July 22, 1947, Serial No. 762,716
In Great Britain June 6, 1945

Section 1, Public Law 690, August 8, 1946
Patent expires June 6, 1965

9 Claims. (Cl. 139—387)

1

This invention refers to curtain heading tapes suitable for pleating or draping of window curtains and the like.

Heretofore, the pleating of window curtains and the like has usually been effected by means of a length, or lengths, of tape provided with draw-cords, the tape being sewn to the curtain heading across the full width of the latter, and, on being gathered upon the draw-cords, causing the curtain heading to become pleated. Frequently, the tape comprises a plurality of tapes, the back one of which is wide and has another, or other narrower front tape or tapes attached to its face at intervals which are relatively short distances apart, suitable to form hook tubes and which substantially define the pitch of the pleating so that the pleats have been relatively small, in fact, more of the nature of "puckers" or small corrugations, which, in conjunction with the resistance of the curtain material, do not lend themselves to uniform and natural draping of the curtain, and, in fact, contribute to drooping of the curtain heading after a period of suspension.

This invention has for its object to provide a curtain heading tape by which the curtain heading will be kept more upright, and the curtain itself will be more logically uniformly and pleasingly pleated, and by rendering the draping or pleating coincident with the natural draping of the curtain material i. e. in wave form suitable to the texture of the material. A further object, in the case of suspension pleating tape, i. e. tape serving for suspension as well as pleating, is to suspend the curtain by means which help in maintaining the desired uniformity of draping, that is to say, waving or something less gathered than pleating.

According to the invention, the improved curtain heading tape comprises a plurality of tapes, one of which is relatively wide and, in use, is attached to the curtain heading for its whole length corresponding to the width of the curtain, and has another and narrower tape, or tapes, attached to its front face at intervals suitable for providing a relatively short free portion, or portions, suitable for a suspension hook, or hooks, to engage, the other and intervening portions of the narrower tape, or tapes, which are relatively long being left free, and said narrower tape, or tapes, being provided with drawcords by which it, or they, may be pleated, and the wider tape and curtain heading thereby caused to become folded, the said intervening free parts of the narrower tape, or tapes, when pleated ex-

2

tending across the entrances to the curtain heading folds, whilst the wide tape conforms to the shape and proportions of the folds.

The question of suitability of size of a hook tube is obviously determined by the consideration that the hooks should be such as is consistent with strength, whilst allowing the curtain to be drawn back into a minimum of space, and similarly the hook tubes should permit easy insertion of the hook, but be small enough to enable the hook to position that part of the tape and not move about therein or drag or distort the front tape from the broader back tape. Thus, for general purposes, $\frac{3}{8}$ " to $\frac{1}{2}$ " is a suitable width for a hook-tube, whilst $\frac{3}{4}$ " or more would be unnecessarily wide and unsuitable within the meaning of this specification.

According to one embodiment of the invention, the improved heading tape comprises one or more lengths of narrow tape, and a single length of wider tape, the narrow tape or tapes being attached at short intervals to the wider tape (woven or stitched) and leaving relatively long free portions, that is to say, longer than is suitable to form hook tubes. The attached portions of the narrow tape (or tapes) will be relatively short and the connections of each of such attached portions will be at two points, lying a slight distance apart and leaving the short intervening portion free and of a width suitable to form a hook-tube. Extending through the narrow tape (or tapes) is a draw-cord, or draw-cords, which will be interlaced through the long free portions of the front narrower tape and pass behind or in front of the short attached portions or through the hook tubes, or behind or through the wider tape at such points.

With such combination of tapes and drawcord, or draw-cords, the gathering or pleating of the narrow tape, or tapes, will result in those portions of the wide tape facing the long free parts of the narrow unattached tape, or tapes, extending rearwardly in the form of relatively large and uniform folds or pleats and assisting the curtain also to have like folds or pleats, which, owing to the size and uniformity of the same, will give a definite and pleasing draping effect to the curtain, both in the heading and the other parts of the curtain.

In the accompanying drawings:

Fig. 1 is a front view of the portion of the heading part of a curtain with one example of the invention applied thereto, and as it appears prior to pleating of the curtain.

Fig. 2 is a repetition of Fig. 1, but after the curtain has been pleated.

Fig. 3 is an end or edge view of Fig. 2.

Fig. 4 is a sectional plan view along line 4—4 of Fig. 2.

Fig. 5 is a further front view of a portion of the heading part of a curtain, with a further example of the invention applied thereto, and as it appears prior to pleating the curtain.

Fig. 6 is a front view of a portion of the pleating tape, embodying two side-by-side hook-tubes.

Fig. 7 is a front view of a portion of the pleating tape embodying a tapered hook-tube.

Figs. 8, 9 and 10 illustrate three examples of curtain suspension hooks for use with the pleating tape.

Fig. 11 is a sectional plan view of a modification adapted to allow of the folds of the curtain heading being "box-pleated."

Fig. 12 is a sectional plan view of the same modification after being "box-pleated."

Referring now to Figs. 1, 2, 3 and 4, *a* is the curtain heading consisting of a portion of the upper part of the curtain folded back upon itself and such folded-back portion sewn to the rear face of the curtain. To the front of the curtain heading is sewn a single wide tape *b*, equal in length to the full width of the curtain, the sewing being along each edge of the tape. To such wide tape *b* is attached, by weaving or sewing, a narrower tape *c*, equal in length to the wide tape *b*, and at each end folded around the end of the wide tape *b*, see Fig. 2. The points of attachment are at *c*¹, *c*², and are repeated at spaced intervals along the whole length of the tape *c*. Those parts of the tape *c* between the points of connection *c*¹, *c*², form hook-tubes *d*, whilst those parts *c*³, of the tape *c* between successive hook-tubes *d* are left free, i. e., not directly connected to the wide tape *b*. Interlaced with such free parts *c*³, and passing behind the hook-tubes *d*, and between the wide tape *b* and the curtain *a*, are draw-cords *e*, *e*, which, at one extremity, are secured to one end of the tape *c* and at their other extremity are left free and extend a short distance, beyond the edge of the curtain heading *a* when in the flat. By means of such draw-cords the free parts *c*³ of the tape *c* may be gathered or pleated, and caused to form a series of small and even pleats, see Fig. 4, whilst those portions of the wide tape *b* between the hook-tubes *d*, and the material of the curtain, are caused to move rearwardly and form relatively large folds *f*, as shown in Fig. 4. After such pleating, the free ends of the draw-cords *e* extend well beyond the edge of the curtain and are tied together, or coiled and tucked into the curtain heading.

For suspending the curtain when pleated to form the large folds (or even when not pleated), suspension hooks are caused to engage the hook-tubes *d* as shown in Fig. 3—such hooks, in turn, engaging the usual curtain rail runners or gliders.

As shown in Fig. 5, there may be a single wide tape *b*, and two narrow tapes *c*, *c*, attached to the wide tape in like manner to the narrow tape of Figs. 1 and 2, the wide tape being secured by sewing along its upper and lower edges, and also centrally to the curtain heading. In this example, suspension hooks will be used which will engage the hook-tubes *d*, *d* of the two narrow tapes *c*, *c*, lying one over the other and thereby serve both to suspend the curtain from the usual carrier rail, and to hold the heading erect.

Instead of the single hook-tubes *d*, there may

be twin hook-tubes as shown in Fig. 6, and in such case "turn-over" hooks of the kind shown in Fig. 9 may be used, the two portions of the hook engaging the division wall of the twin hook-tube, and thus being firmly held in the hook-tubes.

The hook-tubes *d* in Figs. 1, 2 and 3 will usually be parallel-sided, but as shown in Fig. 7, they may be of tapered formation, and the suspension hook be of like formation, as shown in Fig. 10, thereby giving firm support to the curtain, and without requiring to engage the lower edge of the hook-tube and cause crumpling of the same.

The individual hook-tubes *d* will usually be about $\frac{3}{8}$ to $\frac{1}{2}$ an inch wide, and the free parts *c*³ of the tape *c* will be about 2 inches long. They may, however, be longer for example, 3 inches or more, or shorter, say 1 inch. The points of attachment may be mere lines, or there may be spaces between the free parts which spaces may be with or without hook-tubes and of any suitable width such as just two hook-tubes wide, or the width of many hook-tubes, i. e. for purpose of forming a flat portion of curtain in between the waves formed at the free portions.

The hooks used with parallel-sided hook-tubes may be of the kind shown in Fig. 8, which on application to the hook-tubes serve also to grip the draw-cords, and locate the pleating, i. e., prevent creeping of the pleats.

In each example, the folds or pleats of the wide tape may also embody small hook-tubes by which the curtain may be suspended by further hooks, or by which the folds of the tape and curtain may be converted into "boxpleats." An example of such arrangement is shown in Figs. 11 and 12, *g* being the small hook-tubes in one with the wide tape *b*, and with which hooks engage to support the curtain and also to hold the folds in the required "box-pleat" formation.

To allow of uniformity of suspension, the suspension hooks may be linked together by lengths of fine chains, cords, tapes or like flexible connecting means. Or, the usual gliders or runners with which the suspension hooks engage may be connected in like manner.

By means of this invention the curtain is provided with even waves or folds coincident with the draping properties of the curtain material throughout its full depth and width, and prevents, or diminishes, the tendency of the curtain heading to fall or droop. The tape also provides safe means for suspension of the curtain whether it is provided with hook-tubes or whatever other suspension means are to be used than tube-fitting hooks.

What we claim is:

1. A curtain heading tape which comprises a back tape adapted to be sewn adjacent its edges to a curtain, at least one narrower front tape connected to the back tape at spaced intervals to form alternately long and short portions of said front tape unconnected to said back tape, the short portions partially forming hook tubes for receiving suspension hooks, and at least one draw cord which passes through both tapes adjacent their points of connection and passes behind the portions of the back tape opposite said short portions of the front tape, said draw cord also passing in-and-out through the long unconnected portions of the front narrow tape whereby when the draw cord is drawn the curtain heading tape is pleated, the back tape being formed into relatively large pleats and the long portions of the front tape between the short hook tube portions each being formed into a plurality of small pleats

across the front of the corresponding larger pleat of the back tape.

2. A curtain heading tape as set forth in claim 1 in which additional hook tubes are formed in the back tape in the portions thereof opposite the long portions of the front tape.

3. A curtain heading tape according to claim 1 in which each hook tube portion is constructed to provide a pair of hook tubes.

4. A curtain heading tape according to claim 1 in which at least some of the hook tubes are of tapered formation.

5. A curtain heading tape which comprises a back tape adapted to be sewn adjacent its edges to a curtain, a narrower front tape connected to the back tape at spaced intervals to form alternate long and short portions of said front tape unconnected to said back tape, each short portion partially forming a hook tube for receiving a suspension hook, and at least one draw cord which passes through both tapes adjacent their points of connection and passes behind the portions of the back tape opposite said short portions of the front tape, said draw cord also passing in-and-out through the long unconnected portion of the front narrow tape, whereby when the draw cord is drawn the curtain heading tape is pleated, the back tape being formed into relatively large pleats and the long portions of the front tape between the short hook tube portions each being formed into a plurality of small pleats across the front of the corresponding larger pleat of the back tape.

6. A curtain heading tape which comprises a back tape adapted to be sewn adjacent its edges to a curtain, at least one narrower front tape connected to the back tape by being woven therewith at spaced intervals to form alternately long and short portions of said front tape unconnected to said back tape, the short portions partially forming hook tubes for receiving suspension hooks and at least one draw cord which passes

through both tapes adjacent their interwoven points of connection and passes behind the portions of the back tape opposite said short portions of the front tape, said draw cord also passing in-and-out through the long unconnected portions of the front narrower tape whereby when the draw cord is drawn the curtain heading tape is pleated, the back tape being formed into relatively large pleats with the hook tubes located at the ridges thereof, and the long portions of the front tape between the short hook tube portions each being formed into a plurality of small pleats across the front of the corresponding larger pleat of the back tape.

7. A curtain heading tape according to claim 6, in which additional hook tubes are formed in the portions of the back tape opposite the long portions of the front tape.

8. A curtain heading tape according to claim 6, in which each hook tube portion is constructed to provide a pair of hook tubes.

9. A curtain heading tape according to claim 6, in which at least some of the hook tubes are of tapered formation.
